UNITED STATES PATENT OFFICE.

WARNER R. BUXTON, OF LONGMEADOW, MASSACHUSETTS, ASSIGNOR TO BUXTON, INCORPORATED, A CORPORATION OF MASSACHUSETTS.

CASE FOR KEYS AND THE LIKE.

Application filed May 19, 1922. Serial No. 562,132.

To all whom it may concern:

Be it known that I, WARNER R. BUXTON, a citizen of the United States, residing at Longmeadow, in the county of Hampden and State of Massachusetts, have invented new and useful Improvements in Cases for Keys and the like, of which the following is a specification.

This invention relates to improvements in cases for keys and the like and, more particularly, to cases of that type in which the key retaining members are pivotally connected to the case for swinging movement into and out of the latter along arc-like paths of substantially constant radius.

The invention has for one object to provide, in a key case of the type described, an improved form of key retaining member, which is designed to effectively retain the keys under all ordinary conditions of use and to minimize the possibility of accidental dislodgment of the keys.

Another object of the invention is to provide an improved means for mounting the key retaining members in the case for swinging movement and, if desired, for swivelling movement as well.

Another object of the invention is to provide in a key case, wherein the key retaining members are capable of both swinging and swivelling movement, a mounting of such members in the case in such a manner that any one or more thereof may be quickly and conveniently removed from or assembled in the case when desired, and yet are effectively restrained against accidental removal.

A further object of the invention is to provide in a key case a conveniently removable, one piece, pivoted, key retaining member which is bent to form a key retaining loop and has the entrance to said loop so located as to be inaccessible for the insertion and removal of keys except when the member is removed from its pivotal connection.

Other objects and advantages will appear in the following description and in the illustrative embodiment of the invention in the accompanying drawings, in which,—

Figs. 1 and 2 are small scale elevational views showing the key case in open and closed position, respectively;

Fig. 3 is an enlarged fragmentary cross-sectional view showing the improved key

retaining member and one manner of mounting it in the case;

Fig. 4 is a fragmentary rear view of the case, a portion of the back being broken away along the line 4 of Fig. 3 to show the provision for removal of the key retaining member from its pivotal connection;

Fig. 5 is a fragmentary front elevational view of the parts shown in Fig. 3;

Figs. 6, 7, and 8 are enlarged side elevational, end elevational, and plan views, respectively, showing the upper portion of one of the key retaining members;

Figs. 9 and 10 are side and front elevational views, respectively, showing another means for mounting the key retaining members;

Figs. 11 and 12 are cross-sectional and front elevational views, respectively, showing still another way of mounting the key retaining members; and

Fig. 13 is a sectional plan view taken on the line 13—13 of Fig. 11.

Referring to these drawings, the case proper may be variously constructed, as desired, but, by preference, I employ the style of case shown in my prior U. S. Letters Patent No. 1,261,692 granted April 2, 1918. Thus, as shown in Figs. 1 and 2, the case consists of a strip of suitable flexible material, such as leather or the like. The end portions 13 of this strip form flaps and are foldable along lines of fold 14 in overlapping relation with the central portion 15, which forms the back of the case. The flaps 13 may be releasably secured together in any suitable way, as by the interengageable male and female fasteners 16 and 17 respectively. For the purpose of providing a convenient means for pivotally supporting the key retaining members from the back 15 of the case and also for reenforcing the latter and restraining it against transverse bending, I prefer to permanently attach to back 15 near its upper end, and in any suitable manner, as by eyelet rivets 18, a rigid plate 19, which is preferably of thin metal.

According to one form of my invention, the upper end of plate 19 is rolled over until the upper edge thereof abuts, or substantially abuts, the front face of the plate, thereby forming a portion 20 of approximately hollow cylindrical form. In this portion a series of longitudinally spaced

slots 21 are provided, each of which is disposed in a plane substantially at right angles to the axis of portion 20. These slots, which are preferably formed in the plate 5 prior to the rolling up of portion 20, extend throughout the major portion of the circumference of this portion and may, but do not necessarily need to, extend entirely to the edge of the plate, as shown, for 10 such edge abuts the face of the plate and the ends of the slots are thereby closed. The other end of each slot is provided with an enlargement 22 for the purpose of permitting the key retaining members, to be 15 later described, to be conveniently assembled in, or removed from, the hollow cylindrical support 20. The side walls of each slot 21, except for the portion 22 just described, are preferably parallel or substantially so. The openings 22, by preference, are located in the rear wall of the portion 20 for the reason that they are then covered and concealed by the back 15. Such arrangement minimizes the chances of 20 any key retaining member escaping unintentionally from the support 20 through the opening 22 and yet permits the intentional insertion or removal of such member in or from the opening for the back 25 15 is flexible and can be bent back to gain access to the opening.

The key retaining members may, according to some features of the invention, be constructed in any suitable way so long 30 as they afford a suitable key retaining loop and have means adapted for mounting in the support 20. These members are so mounted in the latter as to swing about the axis of the portion into and out of the case along arc-like paths of constant, or substantially constant, radius, and preferably, although not necessarily, each member is capable of swivelling movement—that is, turning about axes substantially at right 35 angles to that of the portion 20.

By preference, however, I employ key retaining members of the type best shown in Figs. 6 and 7. Each of these members is formed from a single piece of suitable 40 material, such as a thin relatively narrow strip 23 of spring metal, for example, which is bent backwardly upon itself to form a key retaining loop 24 and so formed that its side walls naturally tend to abut 45 each other near the upper end of the loop, as at 25. The two ends 26 of the strip 23 which are disposed opposite one another, may be pivotally supported in the case in 50 any suitable way which will prevent access thereto. Preferably, the ends 26 are bent slightly away from one another for the purpose of affording an easy entrance 55 to loop 24. The bending of these ends need be nothing more than a slight offset 60 and a similar offset is provided below the 65

abutting portions 25 for the purpose of forming upper and lower shoulders 28 on opposite faces of the retaining member. The strip 23, as shown in Fig. 8, has a substantially semi-elliptical cross-sectional 70 shape and its sides are grooved as at 29, so as to form upper and lower shoulders 30. The latter are spaced apart a distance substantially commensurate with the thickness of the walls of the hollow, cylindrical 75 portion 20 and the portion 31 between the shoulders is preferably made cylindrical so that it will freely fit and turn and rotate in the slots 21.

In assembling key retaining members in 80 the case, the ends 26 thereof are inserted in an opening 22 until the grooves 29 come into line with the wall of portion 20. The member is then swung, about the axis of portion 20, to cause the grooves 29 to engage the side 85 walls of slots 21, and thereafter swung into the illustrated position. The key retaining members may then be swung into and out of the case about the axis of the portion 20 or may turn or swivel about an axis at right 90 angles thereto.

It is not necessarily essential to the idea 95 of a removable mounting of a pivotal and swivelling hook in a key case to employ the openings 22. Thus, for example, the arrangement shown in Figs. 9 and 10 may be employed. In this case, the ends of each section of the hollow cylindrical portion 20 do not abut plate 19, as above described, but are bent to form spring fingers 33, which 100 abut plate 19 at an intermediate location and then diverge away from the plate to form a tapering entrance 34 between them and the plate. The key retaining members, constructed as above described, are assembled by first laying them flat against the front face of plate 19 and in the location shown by dotted lines in Fig. 10 and pushing them vertically upwards, causing the 105 two ends 26 to enter the entrances 34 between the two adjacent fingers 33 and plate 19 and causing those fingers to yield away from the plate until the said ends are received in the interior of portion 20. The members are then engaged with the side walls of slots 21 110 in the manner above described and are capable of swinging and swivelling in a like fashion.

When the general arrangement, shown in 115 Figs. 3 to 5 inclusive, is employed, the openings 22 need not necessarily be located exactly as there shown, although such location is preferred for the reasons above stated. Another satisfactory way of accomplishing 120 the desired result is shown in Figs. 11 to 13 125 inclusive, wherein the end portion of the hollow cylindrical portion 20 is bent upwardly as at 36, and meets the face of plate 19 at a fairly steep angle. Enlargements 37 (Fig. 13) are made in slots 21 in this steep

portion 36 so that the key retaining members when held flat against plate 19 may be pushed upwardly and the ends 26 allowed to enter portion 20 through the enlargements 5 37. The key retaining members are then engaged with side walls of slots 21 in a manner similar to that above described. The spacing of the shoulders 30 is, however, preferably increased somewhat to facilitate the assembly 10 of the key retaining members with a support of this type. The portion 36 forms a steep slideway down which the key retaining members slide and gravitate into a pocket at the lower part of portion 20. The slide-way 15 makes it very difficult for a key retaining member to accidentally reach the enlargements 37 and become dissociated with its support 20.

A feature of particular importance consists 20 in the type of key retaining member above described, although, as to this feature, the particular details of construction, which have been described as used for connecting the members to the support, are not necessarily 25 essential and may be varied as desired. The important point is that the entrance to the key retaining loop is not accessible for the insertion and removal of keys except when the key retaining member is removed 30 and this feature is important as effectively guarding against accidental dislodgment of the keys from their retaining members under all usual conditions of key case operation.

35 The invention has been disclosed herein, in an embodiment at present preferred, for illustrative purposes, but the scope of the invention is defined by the appended claims rather than by the foregoing description.

40 What I claim is:

1. A key case, comprising, a case forming member of flexible material, a rigid supporting member secured thereto, a rigid key retaining member having near one end a 45 pivotal connection with said supporting member permitting swinging movement of the key retaining member into and out of the case and permitting rotative movement of said key retaining member about an axis substantially at right angles to that of the swinging movement, and means provided on said supporting member to permit removal of the key retaining member, when desired without deformation of said supporting member.

50 2. A key case, comprising, a case forming member of flexible material, a rigid supporting member secured thereto, a key retaining member bent to form a key retaining loop with a single entrance thereto provided between the ends of the member, both said ends being pivotally engaged with said supporting member permitting swinging movement of the key retaining member into and out of the case and permitting rotative

movement of said key retaining member about an axis substantially at right angles to that of the swinging movement, and means provided on said supporting member to permit removal of the key retaining member when desired. 70

3. The combination with a key case, of a supporting member of hollow substantially cylindrical form secured thereto and provided with a substantially transverse slot, a 75 key retaining member having near one end a part received in said slot and shoulders above and below said part slidably and turnably engaged with the inner and outer walls of the supporting member adjacent said slot, said slideable and turnable engagement with said walls constituting the pivotal and swivelling connection with said supporting member and the means for limiting both inward and outward radial movement of said key retaining member. 80

4. The combination with a key case, of a supporting member of hollow substantially cylindrical form secured thereto and provided with a plurality of substantially transverse slots, a plurality of key retaining members each having near one end a part to slide and turn in one of said slots and shoulders above and below said part to engage the inner and outer walls of said supporting member adjacent said slots, whereby each retaining member is free to swing about the axis of the supporting member and turn about an axis at substantially right angles thereto, and an enlargement provided in each slot at one point to permit the upper shoulder of the key retaining member to pass into and out of the interior of said supporting member. 95

5. A key case, comprising, a case forming 105 member of flexible material, a supporting member of hollow substantially cylindrical form secured thereto near one edge thereof, said member provided with a plurality of substantially transverse slots, a plurality of key retaining members each having near one end a part to slide in one of said slots and shoulders above and below said part to engage the inner and outer walls of said supporting member adjacent said slots, whereby each retaining member is free to swing 110 about the axis of the supporting member, and an enlargement provided in each slot to permit the upper shoulder of a retaining member to pass into and out of the interior 115 of said supporting member, the enlargement in the slot being so located as to be normally covered by and concealed by a portion of the case forming member. 120

6. The combination with a key case, of a 125 supporting member of hollow substantially cylindrical form secured thereto and provided with a plurality of substantially transverse slots, a plurality of key retaining members each having near one end a

part to slide in one of said slots and shoulders above and below said parts to engage the inner and outer walls of said supporting member adjacent said slots, whereby each 5 retaining member is free to swing about the axis of the supporting member, and an enlargement provided in each slot at one point to permit the upper shoulder of the key retaining member to pass into and out of the 10 interior of said supporting member.

7. A key case, comprising, a case forming member of flexible material, a rigid supporting member secured thereto, a member formed to provide a key retaining loop with 15 a single entrance thereto provided near one end thereof and having near such end a pivotal connection with said supporting member permitting swinging movement of the key retaining member into and out of 20 the case, and means provided on said supporting member to permit removal of the key retaining member, when desired, said entrance being inaccessible for insertion or

removal of keys in said loop except when removed from said supporting member. 25

8. A key holding device which includes a plate having a slot therein adjacent one edge and an enlarged portion at one end of said slot, the portion of the plate adjacent said edge being bent around so that the 30 enlarged portion of the slot is located at the rear of the plate, a key supporting element having an enlarged head to be inserted in the enlarged portion of said slot and then moved to lie in the smaller portion of the 35 slot, and a folder to which said plate is fastened, the rear portion of the plate having the enlarged portion of the slot therein adapted to lie against the folder to substantially close the slot, whereby the element supporting the keys can move and rotate in the slot but is prevented from being removed therefrom.

In testimony whereof I have affixed my signature.

WARNER R. BUXTON.
